AUTOMATIC BIT SORTER

Howard Johnston, Happy Camp, Calif.

Application August 14, 1945, Serial No. 610,721

14 Claims. (Cl. 209—82)

1

This invention relates to automatic machines for sorting articles according to size or configuration, and it is an object of the invention to provide a machine adapted to receive a continuous stream of articles of varying sizes or shapes, gauge them as to dimensions or configuration, sort them accordingly, and then deliver them into appropriate separate receptacles.

A further object of the invention is to provide a machine capable of sorting articles according to size or configuration with unfailing accuracy.

A further object of the invention is to provide a machine capable of sorting articles according to size or configuration at a high rate of speed.

More particularly, it is an object of the invention to provide an improved sorting machine employing a series of gauges of different sizes that travel continuously around a closed path in order of decreasing size, together with apparatus for feeding the articles to be sorted, one at a time, into the path of the gauges during each cycle thereof for removal by a gauge of corresponding size, and apparatus for receiving articles removed by the gauges and conveying them along paths, determined by the gauge that removes them, into appropriate receptacles or bins.

The specific embodiment of the invention disclosed herein is specially designed for sorting detachable rock drilling bits after they have been dulled, before or after they have been resharpened, to facilitate supplying bits of a uniform size to a workman or machine performing a drilling operation.

The conventional rock drilling bit of the detachable type comprises a cylindrical hollow shank of one diameter and a coaxial cylindrical head of a larger diameter at one end of the shank. While the bit is being used for drilling into rock, its terminal cutting edges become dulled, and the larger outer annular cylindrical surface of the cutting head is subject to wear that gradually reduces the diameter of the head. Usually several replacements of dulled bits are required during the drilling of a single hole; the best results are obtained under most conditions if a worn bit is replaced each time by one about a $\frac{1}{64}$ " to $\frac{1}{32}$ " smaller. A gauge change is adopted so that each replacement drill will follow. This practice makes it important to have the gauges sorted accurately for size, and quickly.

Heretofore, the sorting of bits according to the diameters of their heads has been performed largely by hand, and the task has been time-consuming, tedious, and inaccurate. One method of gauging bits that is commonly employed is to

2

measure the diameters of the heads of the bits along lines coincident with the centers of opposed wings of the cutting end thereof. Another feasible method is to pass the bits through a series of ring gauges until a ring gauge of a size corresponding to the size of the bit has been determined. Both the manufacturers and users of bit-sharpening equipment have spent substantial sums of money and a great deal of time and effort in attempts to perfect a machine that will automatically gauge bits by some method such as one of those described and sort the bits according to size. However, in spite of these efforts and the commercial demand for a satisfactory bit-sorting machine, none has yet been made available.

The machine illustrated herein involves apparatus for feeding bits to be sorted sequentially in sets of gauges by means of a bit support carried on the end of a slender arm, apparatus for moving the sets of gauges continuously around a circular path in timed relation with the feeding apparatus to pick up a bit therefrom during each cycle of each set of gauges, and an arrangement of distributing chutes and bins for separately receiving the bits of different sizes as determined by the particular gauges picking them up from the feeding apparatus. With the machine illustrated, bits may be rapidly sorted according to size with unfailing accuracy.

While this machine has been specially designed for sorting detachable rock drilling bits, it will be apparent from the following disclosure that the basic features of the machine may be readily employed for sorting other types of articles according to size or configuration with the same accuracy and facility. For convenience in terminology, the word "size" will hereinafter be employed in referring not only to the size of an article as a whole, but also to the size of a portion of an article with respect to another portion thereof. In other words, variations in the "configuration" of an article are henceforth intended to be embraced by expressions making reference to variations in "size," and the expression "a machine for sorting articles according to size" will be employed as including a machine for sorting articles according to "configuration."

In the following detailed description of one embodiment of the invention, reference will be made to the accompanying drawings, in which:

Fig. 1 is a side elevation of a machine for sorting detachable rock-drilling bits according to the maximum diameters of their heads;

Fig. 2 is another side elevation of the machine,

showing the opposite side thereof from that shown in Fig. 1 with the wheel advanced 90°, this view being partly in section to expose certain parts that would otherwise be hidden;

Fig. 3 is a fragmentary side elevation similar to a portion of Fig. 2, but with certain parts broken away, illustrating on an enlarged scale the cooperative relation between a magazine for feeding bits to the machine, mechanism for moving bits sequentially from the magazine to a position where they can be gauged, and two sets of gauges and associated parts that are movable continuously around a circular path past the gauging position;

Fig. 4 is a fragmentary sectional view of the machine, the plane of the section being indicated by the line 4—4 in Fig. 3;

Fig. 5 is a fragmentary plan view of the machine, illustrating on an enlarged scale the operation of the mechanism for moving bits sequentially from the magazine to the position where they are gauged, and further illustrating the cooperative relation of certain parts depicted in Fig. 3;

Fig. 6 is an isometric view of the group of receptacles or bins that are disposed to receive bits of different sizes from certain ones of a number of receiving passages that are respectively associated with a corresponding number of gauges;

Fig. 7 is an isometric view of one of a pair of identical chutes that are respectively associated with the largest size gauge in each of the two sets of gauges for guiding bits corresponding in size to those gauges into one of the bins shown in Fig. 6;

Fig. 8 is a fragmentary sectional view of the machine, the plane of the section being just a little off center of the chute illustrated in Fig. 7 and off the centers of the associated gauge and bit receiving bin;

Fig. 9 is another fragmentary sectional view of the machine showing the relation between a second and a third conduit-type chute and a distributing drum assembly, the plane of the section being indicated by the line 9—9 in Fig. 2;

Fig. 10 is another fragmentary sectional view of the machine showing the paths through the distributing drum assembly followed by bits entering it from the second and third chutes, the plane of the section being indicated by the line 10—10 in Fig. 9;

Fig. 11 is another fragmentary sectional view of the machine showing how the entrance ends of the chutes are shaped, the plane of the section being indicated by the line 11—11 in Fig. 10, and certain parts being omitted for clarity;

Fig. 12 is another fragmentary sectional view of the machine after the gauge and chute assembly has been rotated about 45° from the position in which it is shown in Fig. 10 in order to show the second and third chutes in position for discharging bits into a pair of respectively associated bins, the plane of the section through the gauge and drum assembly being indicated by the line 12—12 in Fig. 10;

Fig. 13 is a fragmentary sectional view similar to Fig. 9 but taken along a plane indicated by the line 13—13 in Fig. 2 in order to show the relation between a fourth and a fifth chute and the distributing drum assembly;

Fig. 14 is another fragmentary sectional view of the machine showing the paths through the distributing drum assembly that are followed by bits entering it from the fourth and fifth chutes, the

plane of the section being indicated by the line 14—14 in Fig. 13;

Fig. 15 is another fragmentary sectional view of the machine after the gauge and drum assembly has been rotated about 45° from the position in which it is shown in Fig. 14 in order to show the fourth and fifth chutes in position for discharging bits into a pair of respectively associated bins, the plane of the section through the gauge and drum assembly being indicated by the line 15—15 in Fig. 14;

Fig. 16 is another fragmentary sectional view similar to Fig. 9 but taken through the sixth chute from its position in Fig. 2 with the wheel 26 rotated about 90° counter-clockwise in order to show the relation between this sixth chute and the fixed distributing chute;

Fig. 17 is another fragmentary sectional view of the machine showing the path through the distributing drum assembly that is followed by bits entering it from the sixth chute, the plane of the section being indicated by the line 17—17 in Fig. 16;

Fig. 18 is another fragmentary sectional view of the machine showing the mounting of a jarring mechanism on the gauge and drum assembly for freeing bits lodged in a gauge so they may be readily removed from the gauge by the force of gravity, the plane of the section being indicated by the line 18—18 in Fig. 1; and

Fig. 19 is a view in perspective of one form of bit which can be sorted in this machine.

Referring first to Figs. 1, 2, and 9, the machine may be constructed on a rigid frame 20 including a pair of spaced-apart trusses 21 and 22 between which a cylindrical structure of considerable size may be mounted for rotation, preferably about a horizontal axis. In the embodiment of the invention illustrated in the drawings, a horizontal shaft 23 is mounted adjacent its opposite ends in a pair of journals 24 and 25 that are respectively secured in a suitable manner on top of the trusses 21 and 22.

A centrally apertured disc 26 is mounted on the shaft 23 between the supports 21 and 22 and is rigidly secured to the shaft for rotation therewith. On opposite sides of the disc 26, and forming a rigid structure therewith, a pair of drum segments 27 and 28 are axially mounted on the shaft 23 with an open end of each drum segment abutting the interposed disc to form in effect, a single drum divided interiorly by the disc 26 into two main compartments. The main compartment of one of the drum segments 27 is divided into two smaller compartments by a partition 29, and the main compartment of the other drum segment 28 is divided into three smaller compartments by a pair of partitions 30 and 31. The partitions 29, 30, and 31 are disposed parallel with the disc 26 and are so spaced with respect to the ends of the drum and the disc that five substantially identical annular compartments 32, 33, 34, 35, and 36 are provided within the composite drum.

Bit pick-up mechanism

Two sets of split-ring gauges, having six gauges in each set, are mounted around the periphery of the disc 26, each gauge being supported on the outer end of a radially extending arm 37 that is secured to the disc in any suitable manner, as by welding. All of the radially extending arms 37 may be identical in size and shape, and the six arms for one set of gauges are mounted in uniformly spaced-apart relation around 90° of

the circumference of the disc 26, while the six arms 37 for the other set of gauges are similarly mounted around a diametrically opposed 90° portion of the circumference of the disc 26.

For convenience hereinafter, the split-ring gauges in each set will be identified by the same set of six reference characters. As shown in Fig. 2, the gauges in each set are numbered serially in a clockwise direction by reference characters 41 to 46 inclusive; and the internal diameters of the gauges in each set decrease progressively in the same order, the first gauge 41 being the largest and the sixth gauge 46 being the smallest. As best shown in Figs. 3 and 5, each split-ring gauge is secured to its radially projecting arm 37 by suitable fastening means 47 that pass through the arm and through an extension 48 of the gauge. The several gauges in both sets are mounted so that the axis of the ring portion of each gauge is tangent to a circle that is coaxial with the shaft 23 on which the gauge and drum assembly is mounted; and the gap or space 49 in each of the gauges 41 to 46 is disposed in alignment with those in the others, preferably with the centers of the gaps exactly opposite the points on the rings where the extensions 48 are attached. Thus, as the shaft 23 is rotated, the centers of all the gauges travel along a common circular path, and the gaps in the gauges all travel along a similar common path of larger radius.

Suitable means are provided for rotating the shaft 23, such as a pulley 50 driven by an electric motor 51 through an endless belt 52 (see Fig. 1). The direction of the rotation is such that the gauges 41-46 in each set travel around the shaft 23 in order of decreasing internal diameter. By placing a bit 15 (see Fig. 3) to be sorted in the path of each set of gauges during each revolution of the shaft 23, with the head or cutting end 16 of the bit facing in the direction of movement of the gauges and with the axis of the bit tangent to the path of the centers of the gauges, any gauge having a larger internal diameter than the diameter of the head 16 of the bit will pass by in encircling relation thereto, and any gauge not large enough for this will pass over the shank portion 17 only and will carry the bit along with it. In this manner, one of the gauges in each set can be caused to pick up a bit during each complete revolution of the gauge and drum assembly. In order to insure that no bit will be passed by all six gauges of a set, the sixth gauge 46 is made with an internal diameter smaller than the minimum diameter of the heads of any of the bits to be sorted. By mounting the gauges to travel along a circular path of sufficiently great radius relative to the length of the bits to be sorted, the axes of the bits may be caused to lie for their full lengths sufficiently close to the path of the centers of the gauges so that the deviation from exact coincidence will not interfere with satisfactory operation.

Bit-feeding mechanism

Referring now particularly to Figs. 3 to 5, the mechanism for feeding bits into the path of the split-ring gauges includes a vertically disposed, tubular magazine 55 that is mounted with the axis of the tube lying in the plane defined by the circular path of the centers of the gauges. The tube is supported by a bracket 56 mounted in any suitably rigid manner on a horizontally disposed plate 59 carried by the frame 20. The

lower end of the tube is open, and the side wall of the tube adjacent the lower end thereof is cut away to form an opening 57 permitting a bit 15, dropped shank end first down the tube, to be stopped with its lower end flush with the bottom of the tube and then to be moved horizontally through the opening 57 along a straight line path toward the path of the gauges.

Extending into the magazine tube 55 from opposite sides thereof through a pair of openings 58 therein, are a pair of gripping tongs 60 adapted to support a column of bits 15 in the tube by pressure exerted on opposite sides of the shank of the lowermost bit in the column immediately below the head 16 thereof. The tongs 60 respectively include arms that are disposed in generally parallel relation and extend in a direction away from the path of the gauges to respective pivotal mountings 61 carried by a pair of similar horizontal plates 62 that are in turn secured to the bracket 56, as by welding. Approximately midway between its ends, each tong 60 is provided with a lug 63, and the lugs on the two tongs project toward each other and terminate in spaced-apart cam surfaces 64.

A rotatable arm 65 is mounted on a horizontal shaft 66 for rotation about its mid-point in a vertical plane in the direction indicated by the arrow in Fig. 3, and a wedge-shaped lug 67 is provided on each end of the rotatable arm. The two lugs 67 are disposed so that their common path of rotation about the shaft 66 lies between the cam surfaces of the lugs 63 of the tongs 60, and the width of the lugs 67 on the arm 65 is substantially greater than the space between the lugs 63 on the tongs when the tongs are in gripping engagement with a bit. Thus, each time a lug 67 on the arm 65 is forced between the cam surfaces 64, the tongs 60 are caused to pivot away from each other and to release the lowermost bit in the magazine tube 55. As soon as a lug 67 on the arm 65 has passed between the cam surfaces 64, a helical spring 69, secured under tension at its opposite ends to the two tongs, causes the tongs to pivot toward each other for gripping the succeeding bit in the magazine as it drops into the position formerly occupied by the bit just released. By suitably proportioning the length of the lugs 67 on the arm 65 and the width of the lugs 63 on the tongs 60 for any given speed of rotation of the arm 65, the tongs 60 may be caused to return to their gripping positions at the proper speed to prevent more than one bit being dropped below the tongs during each half revolution of the arm 65.

The arm 65 is caused to rotate at the same angular velocity as the gauges by means of an endless chain 70 acting between a sprocket 71 on the drum shaft 23 and a sprocket 72 of the same dimensions on the shaft 66, whereby one bit is caused to drop from the tongs 60 during every half revolution of the gauge and drum assembly.

An arm 75 is mounted for longitudinal movement directly below the lower end of the magazine tube 55 along a straight line path passing through the center line of the magazine and through the path of the centers of the gauges 41-46. One end of the arm 75 carries a horizontally disposed disc, or table, 76 having a coaxially disposed, cylindrical projection 77 on its surface. The diameter of the projection 77 is slightly smaller than the internal diameter 17 of the shank of a conventional, detachable bit 15 so that the projection will readily fit into the end of the bit, and the diameter of the table 76

is somewhat greater than the diameter of the projection 77, but smaller than the internal diameter of the smallest gauges 46. The width of the arm 75, in a horizontal direction transverse to its path of travel, is less than the width of the gap 49 in each gauge.

At its opposite end from the table 76, the arm 75 is secured in any suitably rigid manner to a movable block 80 that is slidably mounted on a stationary block 81. As shown in Fig. 4, the movable block 80 is provided with a channel 82 in its lower surface and with inwardly projecting horizontal flanges 83 that form a positive guide for the movement of the block 80 on the stationary block 81. The stationary block 81 is supported by a bracket 84 that is in turn supported on the horizontally disposed plate 59 carried by the frame 20.

At one end of its movement, the table 76 on the arm 75 is positioned slightly below the lower open end of the magazine tube 55, and the cylindrical projection 77 extends for substantially its full height up into the magazine tube. When a bit 15 is dropped by the tongs 60, the hollow shank 17 of the bit fits over the projection 77 and rests on the table 76. The arm 75 is then moved along its path of travel toward the path of the center line of the gauges 41-46 and is stopped when the bit (supported on the table 76) is aligned in that path in the manner described above. The dropping of a bit from the magazine 55 and the movement of the arm 75 are timed with the movement of the gauges so that a bit is positioned in the path of the gauges just ahead of the first gauge 41 in one of the sets. As the gauges swing upwardly past the table 76, the table 76 passes through each of them in order, and the narrow arm 75 passes through the gap 49 of each gauge in order. The bit 15 remains supported on the table 76 until its enlarged end 16 becomes lodged in a gauge of a corresponding size and is carried away thereby. As soon as all the gauges in that set have passed by the table 76, the arm 75 is withdrawn until the table 76 thereon is positioned below the magazine 55 to receive another bit. On receiving a second bit, the arm 75 is again moved toward the path of the center line of the gauges 41-46 to position this bit in that path just ahead of the first gauge 41 in the second set of gauges 41-46. As soon as the second set of gauges has passed by the table 76 and the second bit has been removed by a gauge of appropriate size, the arm 75 is again withdrawn, reloaded, and returned with another bit for selection by one of the first set of gauges on its next cycle of travel.

In order to operate the arm 75 in proper timed relation to the dropping of the bits from the magazine and to the cyclical movement of the gauges, the movement of the arm is also controlled by the rotation of the shaft 23 on which the gauge and drum assembly is mounted. To this end, a plate cam 87 is rigidly mounted on the shaft 23, and a cam follower 88 is mounted in horizontally disposed guides 89 carried by the frame 20 for reciprocating movement determined by the contour of the cam 87. The cam follower 88 extends horizontally away from the cam and terminates in a bracket 90 (see Fig. 5), to which a horizontally disposed rod 91 is pivotally secured by means of a vertically disposed pin 92 in the bracket 90. The rod 91 is in turn secured to a parallel link 93 in a manner designed to give some flexibility in the event the arm 75 is to be driven thereby should jam in removing a bit 75

from the magazine 55. The securing means includes three apertured lugs 94 on the link 93 through which the rod 91 extends, and the rod is held in place by a collar 95, rigidly secured to the rod, and by a helical compression spring 96, both of which surround the rod and bear against opposite surfaces of a pair of adjacent lugs 94. The spring 96 is made sufficiently strong to carry the normal thrust applied thereto without substantial compression. A second helical spring 97 is held under tension between a lug 98 on the link 93 and a second lug 99 on one of the cam follower guides 89, whereby the cam follower is urged against the cam 87 at all times.

15 The link 93 is pivotally connected to one end of a cross link 100 by means of a vertically disposed pin 101; the cross link 100 is connected at its opposite end to a third link 102 by means of a vertically disposed pin 103; and the third link 102 is pivotally connected to the movable block 80 by means of a vertically disposed pin 104 that is fixed to the movable block. The cross link 100 is pivoted between its ends on a fixed vertical pin 105 carried by a post 106 that is mounted on the plate 59.

20 With this arrangement, reciprocation of the cam follower 88 drives the rod 91 and link 93 to cause oscillation of the cross link 100; and oscillation of the cross link 100, acting through the third link 102, causes reciprocation of the block 80, the amplitude of movement of the block 80 being determined by the position of the fixed pin 105 between the ends of the cross link 100. The cam 87 is circular in profile except for two oppositely disposed cut-away portions partially bounded by edges 109 of arcuate profile, and the driving connection between the cam 87 and the movable block 80 is so proportioned that the table 76 is disposed below the magazine 55 when the cam follower is riding along either of the arcuate edges 109 and is disposed in the path of the gauges when the cam follower is riding along the intermediate arcuate portions 110 of greater radius.

45 Collecting bins

50 Six bins are employed for receiving bits respectively from the six gauges in each set. The bins are grouped about the machine in a manner best shown in Figs. 1 and 2, and may be secured together in a unitary assembly in the relation shown in Fig. 6 with an outlet in the bottom of each bin for separate removal of bits of different sizes.

55 After a gauge has picked up a bit 15 from the table 76, the bit remains in the gauge until the gauge has rotated beyond the highest point along its path and has tilted sufficiently toward an inverted position when the bit will fall out of the gauge under the influence of gravity. To convey bits from the various gauges into appropriate bins, a separate chute is associated with each gauge. The chutes lead along separate paths through the drum assembly on the shaft 23 and finally out of the drum assembly again to a point from which the bits can fall under the influence of gravity into the appropriate bin. The chutes for one set of gauges are identical in all respects with the corresponding chutes for the other set of gauges, so that only one set of chutes need be described in detail. At this point it should be noted too that while the machine described has two sets of gauges it might have only one or it might have several sets, depending upon the capacity to be handled.

Referring now particularly to Fig. 2, the first gauge 41 in one set is shown at the highest point in its path of travel, just before reaching the position for discharging the bit 15 carried thereby. Ahead of this gauge 41, a channel-shaped chute 111 is mounted on the disc 26 by means of a radially extending bracket 117 that may be secured to the chute and to the disc in any suitable manner, as by welding. The chute 111 is so disposed with respect to its associated gauge 41 that a bit dropping from the gauge will fall into the adjacent end of the chute as the assembly continues to rotate. By the time the bit falls out of the opposite end of the chute 111, gravity and the horizontal component of its own momentum carry it into a bin 121 disposed to receive bits from the gauge 41 of each set. The approximate discharge position of the chute 111 and the path of descent of a bit into the bin 121 are illustrated in Fig. 8.

Referring now to Figs. 9 to 12, and particularly to Figs. 9 and 10, a conduit type of chute 112 is mounted on the drum assembly with one open end 118 thereof disposed with respect to its associated gauge 42 for receiving a bit falling from that gauge when it reaches its discharge position. The conduit 112 leads into the compartment 32 in the drum assembly through an opening 119 and out of the compartment again, through an opening 120 located on the surface of the drum assembly about 80° around the circumference thereof from the inlet opening 119, to a discharge end 127 of the chute. As a bit falls from the gauge 42 down the chute 112 into the compartment 32, the rotation of the drum assembly carries the discharge end 127 of the chute to a point above a bin 122 (see Figs. 6 and 10) disposed to receive bits from gauge 42 of each set. A baffle 123 that projects beyond the discharge end 127 of the chute 112 prevents bits discharged from this chute from falling into an adjacent bin 123 for bits of the next smaller size.

A conduit type of chute 113, similar to the chute 112 for the second largest gauge 42, is associated in a like manner with the third gauge 43, one open end 129 of the chute 113 being disposed to receive bits falling from the associated gauge. The chute 113 leads into the compartment 33 in the drum assembly and out again, in the same manner that the chute 112 passes through the compartment 32, and terminates in a discharge end 130. By the time a bit falling through the chute 113 reaches the discharge end thereof, rotation of the drum assembly has carried the discharge end of this chute into position for the bit to drop therefrom into a bin 123 disposed to receive bits from the gauge 43 of each set. A baffle 131 that projects beyond the discharge end 130 of the chute 113 prevents bits discharged from this chute from falling into the adjacent bin 122 for bits of the next larger size.

In a similar manner, bits are conveyed from the fourth and fifth largest gauges 44 and 45 through similar respectively associated conduit type chutes 114 and 115 that lead through the compartments 34 and 35 respectively in the drum assembly and terminate in projecting discharge ends 134 and 135 respectively, as shown in detail in Figs. 13 and 14. By the time bits falling through these chutes reach the discharge ends 134 and 135 thereof, rotation of the drum assembly has carried these discharge ends into positions for the bits to drop therefrom into respectively associated bins 124 and 125, as shown in Fig. 15.

In a like manner, bits are conveyed from the

smallest gauge 46 through an associated conduit type chute 116 that leads into the compartment 36 in the drum assembly, as shown in Fig. 16. In this instance, however, the chute terminates where it joins an inlet opening 136 for the associated drum compartment. A partition 137 divides the compartment diametrically into two, equal, smaller compartments, as shown in Fig. 17. A bit falling from one of the chutes 116 into an associated one of these smaller compartments is finally discharged therefrom through an opening 138 in the adjacent end of the drum assembly and falls into an appropriately disposed bin 126.

The bit jarring mechanism

When a bit 15 is picked up by one of the split gauge rings 41, 42, 43, 44, 45, or 46, it is apt to become lodged therein so tightly that it cannot fall therefrom when the gauge reaches the normal discharge position. To prevent such an occurrence, a gravity operated jarring mechanism is associated with each gauge. As shown in Figs. 1, 2, 9 and 18, a pair of similar, longitudinally arcuate bars 140 and 141 for each set of gauges are secured at their ends to a pair of radially disposed supporting plates 142 and 143 which are in turn secured to the perimeter of the disc 26 that carries the gauges. The two supporting plates 142 and 143 are identical except that the plate 143 is provided with a radially projecting lug 144 on its outer edge midway between the adjacent ends of the arcuate bars 140 and 141, as shown in Fig. 18. The bars 140 and 141 respectively pass along opposite sides of all the gauges in the set with which they are associated, and an identical set of bars 140 and 141 are associated in the same manner with the other set of six gauges. Behind each gauge is a separate, pivotally mounted shaft 145 that is mounted in a pair of journals 146 respectively carried by the two adjacent bars 140 and 141. Each shaft 145 terminates at one end in a hub 147 from which another rod 148 projects in a radial direction with respect thereto, and a collar-shaped weight 149 is fitted over the radially disposed rod 148 and is secured in place in a suitable manner, as by a set screw, to permit longitudinal adjustment of its position thereon. Midway between the journals 146, each shaft 144 is provided with a lug 150 that projects radially therefrom at an angle of about 130° with the radially projecting rod 148.

When the drum assembly is rotated in a counterclockwise direction as the assembly is viewed in Fig. 2, the weights 149 cause the shafts 145 to oscillate between two extreme angular positions. The extreme counterclockwise position is illustrated in Fig. 2 by the first three jarring devices associated with the first three gauges 41, 42, and 43 in the upper set of gauges. In this position, the lug 150 of each jarring device rests against the opening in the underside of its associated gauge with the end of the lug projecting into the center of the gauge. If there were a bit in any of these gauges the lug 150 would have loosened it as it swung into this position. The extreme clockwise position is illustrated in Fig. 2 by jarring devices associated with the gauges 45 and 46 of the upper set of gauges. In this position, the lug 150 of the jarring device for gauge 45 rests against the chute 116, and that for the gauge 46 rests against the lug 144 on the adjacent supporting plate 143 for the arcuate bars 140 and 141.

The jarring device associated with the gauge 44 is in the process of swinging from the position

against the chute 115 to its extreme counterclockwise position with the lug 150 against the gauge 44. With the parts in the position shown in Fig. 2 the weight 149 on the jarring device for gauge 44 has just crossed the point of top dead center and is falling, causing the lug 150 to move counterclockwise.

As the gauges descend from their uppermost position, the associated jarring devices 150 rotate clockwise to their extreme clockwise position, and they are then held in that position by gravity.

The counterweight 149 brings the lug 150 up against the next adjacent chute (e. g. the lug 150 for gauge 41 will come against the chute 112). This stops the clockwise movement and the counterweight 149 is carried around as in the positions shown in the lower set of gauges in Fig. 2 and the upper ones for gauges 45 and 46.

The effectiveness of the weights 149 in controlling the jarring mechanisms may be increased by adjusting the positions of the weights along their respective supporting rods 148.

As will be apparent from the foregoing, operation of the machine merely requires that the magazine 55 be loaded with bits 15 to be sorted and that the motor 51 be driven at a substantially constant speed. By initially coordinating the action of the tongs 60 and of the bit positioning arm 75 with the rotation of the gauge and drum assembly, a bit will be automatically positioned in the path of each set of gauges during each revolution of that set, and will be picked up by a gauge in that set of proper size, dropped into the associated chute, and finally conveyed into the bin associated with that chute.

While a specific embodiment of the invention has been described in detail in compliance with U. S. Rev. Stat., Sec. 4888, it will be obvious to those skilled in the art that numerous modifications thereof may be made while employing the essential principles of its construction and operation. What is claimed is:

1. A machine for sorting articles according to size, comprising a plurality of gauges each having an aperture therethrough of a different size from the others and similar in profile to the articles to be sorted, means for cyclically moving said gauges around a predetermined closed path in order of decreasing aperture size, and means for aligning one of the articles to be sorted in a position in said path ahead of said gauges during each cycle so that the article will lodge in the aperture of a gauge of appropriate size as the gauges pass said position.

2. A machine for sorting articles of circular cross-section according to their maximum diameters, comprising a plurality of ring gauges of different internal diameters, means for cyclically moving said gauges around a predetermined circular path in order of decreasing internal diameter, and means for centering one of the articles to be sorted in said path during each cycle for selective removal by a gauge of appropriate size.

3. A machine for sorting articles of circular cross-section according to their maximum diameters, comprising a plurality of split ring gauges of different internal diameters, means for cyclically moving said gauges around a predetermined circular path in order of decreasing internal diameter, and means for positioning one of the articles to be sorted in said path during each cycle for selective removal by a gauge of appropriate size, said positioning means being supported by an arm capable of passing through the split of each split ring gauge.

4. A machine for sorting articles of circular cross-section according to their maximum diameters, comprising a plurality of split ring gauges of different internal diameters, means for cyclically moving said gauges along a predetermined circular path in order of decreasing internal diameters, means operative to position said articles to be sorted sequentially in said path, and means for operating said positioning means in coordinated relation with the movement of said gauges such that one of said articles is positioned in said path ahead of said gauges during each cycle of movement thereof, said positioning means being supported by an arm capable of passing through the split of each split ring gauge.

5. A machine for sorting articles of circular cross-section according to their maximum diameters, comprising a plurality of split ring gauges of different internal diameters mounted on a horizontal shaft for rotation therewith along a predetermined circular path in order of decreasing internal diameter, a magazine for feeding the articles to be sorted to the machine, means operative to receive said articles sequentially from said magazine and position them sequentially in said path, and means controlled by rotation of said shaft for operating said positioning means to position one of said articles in said path ahead of the gauges during each revolution thereof, said positioning means including a supporting arm capable of passing through the split of each split ring gauge as it passes thereby.

6. A machine for sorting articles of circular cross-section according to their maximum diameters, comprising a plurality of sets of split ring gauges mounted in spaced-apart relation circumferentially around a horizontal shaft for rotation along a predetermined circular path, each set of gauges comprising a plurality of individual gauges of different internal diameters disposed in spaced-apart relation along said path in order of decreasing internal diameter, a magazine for feeding said articles to be sorted to the machine, means operative to receive said articles sequentially from said magazine and position them sequentially in said path, and means controlled by rotation of said shaft for operating said positioning means to position an article in said path ahead of each set of gauges during each revolution thereof, said positioning means including a supporting arm capable of passing through the split of each gauge as it passes thereby.

7. A machine for sorting articles according to size, comprising a plurality of gauges of different sizes mounted in circumferentially spaced-apart relation for rotation along a predetermined path about a horizontal axis, each of said gauges being adapted to pick up an article of a corresponding size at a point in said path, a corresponding plurality of chutes mounted for rotation about said axis and respectively associated with said gauges, each chute being disposed with respect to its associated gauge for receiving therefrom an article picked up thereby.

8. A machine for sorting articles according to size, comprising a plurality of gauges of different sizes mounted in circumferentially spaced-apart relation for rotation along a predetermined path about a horizontal axis, each of said gauges being adapted to pick up an article of a corresponding size at a point in said path, a corresponding plurality of chutes mounted for rotation about said axis and respectively associated with said gauges, a corresponding plurality of stationary bins re-

spectively associated with said chutes, each chute being disposed with respect to its associated gauge for receiving therefrom an article picked up thereby and being shaped to discharge an article it receives into its associated bin.

9. A machine for sorting articles of circular cross-section according to their maximum diameters, comprising a plurality of ring gauges of different internal diameters mounted for rotation in order of decreasing internal diameters along a predetermined circular path, a magazine for feeding articles to be sorted to the machine, means for receiving articles sequentially from said magazine and positioning them sequentially in said path in a predetermined timed relation with the travel of said gauges, whereby a gauge of appropriate size will pick up one of the articles during each revolution of the gauges, a plurality of chutes corresponding to the number of gauges mounted for rotation with the gauges and respectively disposed in association therewith for receiving articles picked up thereby, and a plurality of stationary receiving hoppers corresponding to the number of chutes respectively associated therewith and disposed for receiving from the respectively associated chutes the articles received by the chutes from the respectively associated gauges.

10. A machine for sorting articles according to size, comprising a plurality of gauges each having an aperture therethrough of a different size from the others and similar in profile to the articles to be sorted, means for cyclically moving said gauges around a predetermined closed path in order of decreasing aperture size, means for causing one of the articles to be sorted to lodge in the aperture of one of the gauges during each cycle and means associated with the gauges for freeing an article lodged therein for subsequent removal.

11. A machine for sorting articles according to size, comprising a plurality of gauges each having an aperture therethrough of a different size from the others and similar in profile to the articles to be sorted, means for cyclically moving said gauges around a predetermined closed path in order of decreasing aperture size, means for causing one of the articles to be sorted to lodge in the aperture of one of the gauges during each cycle, and a corresponding plurality of means respectively associated with said gauges for free-

ing articles lodged therein for subsequent removal.

12. A machine for sorting articles according to size, comprising a plurality of gauges each having an aperture therethrough of a different size from the others and similar in profile to the articles to be sorted, means for cyclically moving said gauges around a predetermined closed path in order of decreasing aperture size, means for causing one of the articles to be sorted to lodge in the aperture of a gauge of appropriate size during each cycle, and a corresponding plurality of means respectively pivotally mounted on said gauges for gravity operation at a predetermined point along said path to free articles lodged in the gauges for subsequent removal.

13. A machine for sorting articles of circular cross section according to their maximum diameters comprising a plurality of split ring gauges of different internal diameters, means for moving said gauges past a certain point in order of decreasing internal diameter, and means for positioning one of the articles to be sorted at said point and in the path of said gauges for selective removal by a gauge of appropriate size, said positioning means being supported by an arm capable of passing through the split of each split ring gauge.

14. A bit-sorting machine comprising a plurality of split ring gauges of different internal diameters, means for moving said gauges upwardly past a point in order of decreasing internal diameter, and means for positioning one of said bits at said point for selective removal by a gauge of appropriate size, said positioning means being supported by an arm capable of passing through the split of each split ring gauge.
